DESIGN FOR A KNIFE

Alfred O. Beisang, St. Paul, Minn., assignor to Brown & Bigelow, St. Paul, Minn., a corporation of Minnesota

Application April 24, 1936, Serial No. 62,283

Term of patent 3½ years

To all whom it may concern:

Be it known that I, Alfred O. Beisang, a citizen of the United States, residing at St. Paul, county of Ramsey, and State of Minnesota, have invented a new, original, and ornamental Design
for Knives, of which the following is a specification, reference being had to the accompanying drawing, forming part thereof:

Figure 1 is a plan view of a knife, showing my new design.

but showing the parts in different relation.

Figure 3 is a side elevational view of my knife

Figure 4 is a plan view of my knife in open position.

Figure 5 is an end view of my knife, as shown in Figures 2 and 3.

I claim:

The ornamental design for a knife, as shown:

ALFRED O. BEISANG.
